FOREIGN PATENT DOCUMENTS

EM 1380455-0001 8/2013

Primary Examiner — Cynthia M Chin*(74) Attorney, Agent, or Firm* — Malloy & Malloy, P.L.(57) **CLAIM**

The ornamental design for an elevated sun platform, as shown and described.

DESCRIPTION

FIG. 1 is a front perspective view illustrating my design for an elevated sun platform;

FIG. 2 is a rear perspective view thereof;

FIG. 3 is a top plan view thereof;

FIG. 4 is a bottom perspective view thereof;

FIG. 5 is a front view thereof;

FIG. 6 is a rear view thereof;

FIG. 7 is a left side view thereof; and,

FIG. 8 is a right side elevation view thereof.

The broken lines shown are included for the purpose of illustrating the unclaimed portions of the article and forms no part of the claimed design.

1 Claim, 8 Drawing Sheets---
